UNITED STATES PATENT OFFICE.

GELSTON SANFORD, OF BROOKLYN, NEW YORK.

MACHINE FOR OBTAINING FIBERS FROM LEAVES OR PLANTS.

SPECIFICATION forming part of Letters Patent No. 321,536, dated July 7, 1885.

Application filed September 29, 1884. (No model.)

To all whom it may concern:

Be it known that I, GELSTON SANFORD, of the city of Brooklyn, in the county of Kings and State of New York, have invented a new 5 and useful Improvement in Machines for Obtaining Fibers, of which the following is a specification.

My invention is more particularly intended for cleaning or treating the leaves or other 10 parts of fiber-bearing plants while in a green state; and an important object of the invention is to provide a small and portable machine, which may be sold at a low price, and which may be operated either by a hand-crank 15 or foot-treadle, or by power.

In my improved machine I employ an endless chain or belt of scrapers, which is supported and moved by pairs of wheels or flanges, which engage with the chain or belt, and so 20 move it continuously in one direction, the portion of the chain or belt which is between the pairs of supporting-wheels or flanges being made to move in a straight line, and preferably in a line which is vertical, or nearly so. 25 The pintles or joint-pins of the chain or belt are provided at the ends with rollers, which run upon straight tracks which extend throughout the operative portion of the chain or belt, and so hold the scrapers to a straight 30 line and prevent their yielding away from the work while operative. The upright or other side frames, which support the above-described moving parts of the machine, are provided with ribs or guards, which just permit 35 the pintles or joint-pins of the chain or belt of scrapers to pass easily between them, but which prevent the rollers from slipping off the pintles or joint-pins. At the front of the machine is a board or plate, which has a flat inner surface and forms a support for the leaves 40 while under the action of the scrapers. This board or plate is hinged at the lower edge, so that it can be swung outward to place the leaves upon it and remove them from it. I 45 also employ a brush, which may be rotary or stationary, past and in contact with which the scrapers are carried, and by which they are cleaned.

The invention consists in novel combinations

of parts, hereinafter described and pointed 50 out in the claims.

In the accompanying drawings, Figure 1 is a front elevation of a machine embodying my invention. Fig. 2 is a vertical section thereof in a plane at right angles to the front. Fig. 55 3 is a horizontal section on the dotted line xx , Fig. 2; and Fig. 4 is a sectional view upon a larger scale of a portion of the chain or belt of scrapers.

Similar letters of reference designate corresponding parts in all the figures.

The frame of the machine may be of any suitable construction and material. As here shown, it consists of a base portion, A, supported by feet or legs A', and upright side 65 plates or pieces, B B, surmounted by a top plate or piece, B'. All these parts may be bolted together or otherwise securely connected.

C C' designate upper and lower shafts journaled in bearings in the side plates or pieces, B B, and having secured fast upon them pairs of wheels or flanges C', which support and impart motion to an endless chain or belt of scrapers, which I shall soon describe.

The lower shaft, C', by preference, is the one which is positively rotated to give motion to the chain or belt of scrapers. It may be operated by hand, and to this end is provided with a fly-wheel, C², in which is fixed a handle or hand-crank, a; or it may be operated by foot-power, and to this end has at the end opposite the fly-wheel C² a small crank, b, connected by a pitman or rod, c, with a treadle, D. This treadle may consist of a straight lever or 80 piece, D, and a brace or piece, D', offset therefrom, as shown in Fig. 3. The fulcrum pins or pivots d of the treadle may be fixed in the legs or feet A', as best shown in Fig. 3, and on these the treadle may work.

In lieu of separate pivots d, a single rod might be extended between the opposite legs, A', as indicated by dotted lines in Fig. 3.

The chain or belt of scrapers may be of any suitable construction. As here shown, it consists of a series of plates, E, which are about equal in length to the space between the side plates or pieces, B, and are provided with in-

termatching lugs or ears *e*, through which are inserted pintles or joint-pins *f*, whereby the plates are connected like the leaves of a hinge. The plates *E*, with their lugs or ears, are preferably of cast metal, and each has on its outer face a projecting flange, *e'*, to which a scraper or scraping-blade, *g*, is bolted or riveted.

Upon the ends of the pintles or joint-pins *f* are fitted small rollers *f'*. These rollers might 10 be secured by riveting over the ends of the pins, if desired; but I prefer to form the plates *B B* with raised ribs or surfaces *h*, as shown in Fig. 3. The ends of the pins travel very close to these ribs *h*, and the latter form guards 15 which prevent the rollers from slipping off the pins.

The flanges or wheels *C²* have notches in their edges, which receive or engage with the rollers *f'*, and so drive the chain or belt of 20 scrapers in the direction indicated by the arrows, Fig. 2.

In order to compel the descending portion 25 of the chain of scrapers to travel in a straight line in descending, I provide on the side plates, *B*, straight tracks or ways *i*, on which the rollers *f'* run, and whereby the scrapers are prevented from yielding backward while in operation. I have here shown similar tracks or ways, *i'*, at the back of the machine for the ascending portion of the chain of scrapers; but 30 these are not indispensable.

At the front of the machine is a board or plate, *F*, hinged at the lower end and capable of being swung inward to the position shown 35 in Fig. 2 by full lines, or outward to the position there shown by dotted lines.

I have here shown hook-bolts *j* as inserted 40 through the plate or board *F*, and engaged with a cross-rod, *k*, thus forming a hinge, and in order to permit the board or plate to yield forward slightly I place under the nuts of the bolts *j* springs *j'*, which may consist of blocks 45 of india-rubber or of metal.

The upper edge of the plate or board *F* is 45 armed with a serrated plate, *l*, and the said board is provided with a handle, *m*, which extends upward and has a horizontally-extending portion, *m'*. The handle is connected with the plate or board *F* at one side only, 50 and hence affords an opening on the other side for the placing of the leaves on the board.

To use the machine, the front plate or board, *F* is swung forward to the position shown in Fig. 2 by dotted lines. The leaf is laid on the 55 front or inner side of the plate or board with its upper end pressed down over the serrated plate *l*. The plate or board is then swung inward and there held by the handle *m m'*, the same hand which holds said handle grasping 60 a projection or rib, *n*, on the top plate, *B'*, of the frame. The chain of scrapers is then put in operation, and as they descend they scrape and clean the leaf, which is supported by the flat inner surface of the plate or board, and is 65 held against them with a yielding pressure, owing to the spring-cushions *j'*.

It is desirable to clean the scrapers to free them from the substance scraped from the leaves, and to this end I provide a brush past 70 or in contact with which the scrapers are carried. I have here shown a revolving brush, *G*, supported at the back of the machine and operated by a wheel and pinion, *o o'*, from the upper shaft, *C*. This brush turns in the direction indicated by the arrows, Fig. 2, and 75 thereby cleans the scrapers and frees them from any accumulation of gummy vegetable matter.

The hinged front plate or board, *F*, does not extend to the top of the machine, but the space 80 above it is closed by a plate or guard-plate, *p*, which is held in place by bolts *p'* inserted through slots * in the plate and lugs or ears 85 on the side pieces or plates, *B*. This plate *p* should be adjusted downward until it just permits the serrated plate *l* to pass under it, when the front board or plate, *F*, is swung inward. The guard-plate *p* then not only prevents the 90 hands of the operator from coming in the way of the scrapers, but also holds the leaf down in engagement with the serrated plate *l*, and gives the latter a strong hold on the leaf.

What I claim as my invention, and desire to secure by Letters Patent, is—

1. In a machine for obtaining fibers, the 95 combination, with an endless chain of scrapers and wheels and shafts for operating the same, of a board or plate on which the leaves are supported while under the action of the scrapers, and which is movable away from the 100 scrapers to provide for placing leaves thereon and removing leaves therefrom, substantially as herein described.

2. In a machine for obtaining fibers, the 105 combination, with an upright chain or belt of scrapers and wheels and shafts for operating the same, of a board or plate for supporting leaves while under the action of the scrapers, and hinged at the lower end to provide for placing leaves thereon and removing them 110 therefrom, substantially as herein described.

3. The combination, with the upright chain or belt of scrapers and wheels and shafts for operating the same, of the front plate or board, *F*, having a yielding or elastic hinge-support 115 at the lower end, substantially as herein described.

4. The combination, with the upright chain or belt of scrapers and shafts and wheels for operating the same, of the front plate or board, *F*, hinged at the lower end and provided at the upper end with a handle attached to the plate or board at one side only, whereby an opening is left at the other side for placing leaves on and removing them from said plate 125 or board, substantially as herein described.

5. The combination, with the chain or belt of scrapers and shafts and wheels for operating the same, of the hinged front plate or board, *F*, armed at the upper edge with a serrated 130 plate, *l*, substantially as herein described.

6. The combination, with the chain or belt

of scrapers and shafts and wheels for operating the same, of the hinged front plate or board, F, armed with a serrated plate, *l*, and the adjustable guard-plate *p*, substantially as herein described.

5 7. The combination, with the chain or belt of scrapers and shafts and wheels for operating the same, of a brush past and in contact with which the scrapers are moved and a plate or board for supporting leaves while under the action of the scrapers and movable to provide for placing leaves thereon and removing them therefrom, substantially as herein described.

15 8. The combination, with an endless chain or belt of scrapers having rollers upon its pintles or joint-pins, of shafts and pairs of wheels or flanges for operating said chain, a movable front plate or board for supporting leaves while under the action of the scrapers, and tracks or ways on which the said rollers travel and by which that portion of the chain which is operative is prevented from yielding away from the supporting plate or board, substantially as herein described.

9. The combination, with a chain or belt of scrapers, consisting of plates E, severally provided with scrapers and pintles or joint-pins connecting said plates, of shafts and wheels for operating said chain of scrapers and a 30 movable front plate or board for supporting leaves while under the action of the scrapers, substantially as herein described.

10. The combination, with the endless chain of scrapers, consisting of plates E, having intermatching lugs or ears *e*, pintles or joint-pins *f*, and rollers *f'* on said pins, of the side plates or pieces, B, provided with ribs or surfaces *h*, past and close to which the ends of the pintles *f* move, and which form guards to 35 40 keep the rollers on said pintles, and a movable front plate or board, F, for supporting leaves, substantially as herein described.

GELSTON SANFORD.
